UNITED STATES PATENT OFFICE

ROBERT H. BUCK, OF ALAMEDA, CALIFORNIA

NAIL

Application filed December 13, 1926. Serial No. 154,352.

My invention relates to nails useful as furring devices usually employed to maintain a screen spaced from a wall for the reception of plaster, and relates especially to furring devices adapted to be installed at intervals on a wall to support and position the adjacent screen.

An object of my invention is to provide a nail which forms a simple and effective furring device.

10 Another object of my invention is to provide a furring nail which will grip firmly the material to be supported.

An additional object of my invention is to provide a furring device in which the gripping action is effected simultaneously with the action which drives the device into the support.

My invention possesses other advantageous features, some of which with the foregoing, 20 will be set forth at length in the following description where I shall outline in full that form of the nail of my invention which I have selected for illustration in the drawings accompanying and forming part of the present specification. In said drawings I have shown one form of nail embodying my invention, but it is to be understood that I do not limit myself to such form since the invention, as set forth in the claims, may be embodied in 25 a plurality of forms.

In the drawings:

Fig. 1 is a plan view showing one form of the furring nail of my invention in use.

Fig. 2 is an elevation of a modified form of 35 nail.

Fig. 3 is a plan view of the nail shown in Fig. 2, a pair of wires being shown in gripped position.

Fig. 4 is an elevation of a second modified 40 form of the nail.

Fig. 5 shows the form of nail of Fig. 2 as it is utilized on a support such as a wall, the nail being in elevation and the remainder of the view being in cross section.

45 My invention preferably comprises a nail having lips formed by turned down portions of the nail head, the lips preferably cooperating with a spacer to grip the body to be supported.

50 With the increased use of stucco construc-

tion for buildings, it has become customary to affix the plaster by means of wire lath or screen secured to the walls of the building. In order to provide a firm hold for the plaster on the screen or metal lath it is essential that the lath be spaced somewhat from the solid backing of the wall. Various types of spacing devices have been used from wooden furring strips which are nailed to the wall and in turn support the lath or screen to sundry metallic devices which space the screen from the wall and hold it with the cooperation of securing devices such as nails. Most furring devices either require a preliminary application of spacers prior to the positioning of the metal lath and an additional application of supporting members to hold the lath on the spacers or are otherwise complicated in handling or manufacture. My furring device can in a single operation be fixed to the wall and firmly clamp the wire screen or lath to be supported.

In the preferred form of my invention I preferably provide a nail having a shank 6 of the usual kind which is pointed at one end as at 7 for convenient driving into a support such as a wooden stud 8. At the opposite end of the nail, a head 9 is provided. The head is preferably a plane or disc forming an integral portion of the shank 6 and is disposed perpendicularly thereto. The disc is of relatively thin metal and is advantageously of circular contour. To provide means for gripping a body to be supported, such as the strands 11 of metal lath or screen used in stucco construction, I preferably bend or otherwise deform portions of the periphery of the relatively thin head 9 of the nail and cause them to lie substantially at right angles to the main portion of the plane head 9. These downturned portions form lips 12 which lie substantially parallel to the shank 6 of the nail. The lips 12 may be of any desired number. In Fig. 4 I show a form of nail having but one lip, while in Figs. 2, 3 and 5 I show a preferred form of nail having two, equally spaced peripheral lips 12. In Fig. 1, I have shown a three lipped furring nail in use with a metallic screen sometimes termed "chicken" wire.

In order to form a firm seat for the lips 12 and also to space the metallic screen the requisite distance from the wall 8, I have provided a collar or spacer 13 preferably made of compressible or fibrous material, such as felt, or gun wadding. The spacer 13 is preferably an annulus which is slidable upon the shank 6 of the nail, and is placed on the nail prior to the driving of the nail into the support 8. When the nail is driven home, the lip or lips 12 engage the spacer 13 and compress it slightly, thereby forming one or more tubular passages in which the wires 11 are firmly held.

15 While the nail of my invention can be originally formed in the shape shown in the drawings, it is also possible to take standard nails having flat, thin heads, usually termed roofing nails, and by deforming peripheral portions of the heads, manufacture nails of the type shown herein. With the addition of a collar or spacer of felt or similar material, an excellent furring device is provided. It will be appreciated that with the device 23 of my invention, the metal lath or screen is firmly supported at a definite distance from the support and is tightly gripped in place. The blow of the hammer which drives the shank of the nail into the support is also sufficient to force the lips of the head against the spacer and cause the wires to be tightly grasped and firmly held in place.

Although the nail with the single lip may be used, as shown in the upper portion of 35 Fig. 1, I preferably use a nail having two or more lips as the head is then supported equally well on both sides of the shank. The nail with a plurality of lips is less liable to become bent due to one lip striking the spacer 40 or the support and cocking the head at an angle.

I claim:

1. A nail comprising a shank, and a relatively thin head mounted perpendicularly on 45 the end of said shank, peripheral portions only of said head being turned toward said shank.
2. A furring device comprising a nail having a shank and a relatively thin, plane head 50 substantially perpendicular to said shank; and a lip formed by a portion of said head bent toward said shank.
3. A furring device comprising a nail having a shank, a relatively thin flat head there- 55 on substantially at right angles to said shank; a lip formed on a portion of said head, said lip being substantially flat and parallel to said shank; and a spacer slidable on said shank, said spacer being substantially larger 60 than said thin flat head.

In testimony whereof, I have hereunto set my hand.

ROBERT H. BUCK.
